UNITED STATES PATENT OFFICE.

WILLIAM D'H. WASHINGTON AND FREDERICK C. GOODWIN, OF NEW YORK,
N. Y., ASSIGNORS TO THE WASHINGTON-GOODWIN METER COMPANY, OF
WEST VIRGINIA.

LIQUID-METER.

SPECIFICATION forming part of Letters Patent No. 643,432, dated February 13, 1900.

Application filed May 29, 1899. Serial No. 718,766. (No model.)

To all whom it may concern:

Be it known that we, WILLIAM D'H. WASHINGTON and FREDERICK C. GOODWIN, citizens of the United States, residing at New York, 5 in the county of New York and State of New York, have invented certain new and useful Improvements in Liquid-Meters, of which the following is a specification, reference being had therein to the accompanying drawings.

10 The invention relates generally to meters and has particular reference to an improved water-meter adapted for use in measuring the quantity of water drawn from the mains for use in houses or factories.

15 The principal object of our invention is to produce a meter of the kind referred to comprising in its formation but few and simple parts, the latter being so arranged and constructed as to be readily removed when worn 20 to allow of new parts to be substituted in their places or adjusted relatively to each other to compensate for their wear.

With this object in view our invention consists in a novel type of water-meter and in the 25 peculiar construction, arrangement, and combination of the various parts thereof, as more fully hereinafter described, and shown in the drawings, in which—

Figure 1 is a horizontal sectional view on 30 line $y-y$ of Fig. 2. Fig. 2 is a sectional view taken on the line xx of Fig. 1. Fig. 3 is a sectional perspective view, the section being on line zz , Fig. 2. Fig. 4 is a perspective view of the lower section of the meter-casing. Fig. 35 5 is a sectional view similar to Fig. 2, illustrating a modified form of backing.

The reference-letter A designates a cylindrical meter-casing comprising a lower section or body B and an upper section or top C. 40 The lower section is provided with a central recess D, formed in the lower side or wall thereof, and the upper section has formed therein a corresponding recess E. Fixedly secured by means of suitable bolts a to the 45 meter-casing is a housing F, in which is arranged the usual reducing-gearing for the meter.

Within the cylindrical meter-casing is arranged a rotary piston G of less diameter than 50 the casing and arranged concentrically within

the latter, forming an annular passage H, surrounding the piston. Within this passage and preferably diametrically arranged are inclines I and J, the incline I having formed therein a port b, which leads into the supply- 55 pipe K of the meter, and within the incline J is formed a similar port, which communicates with a discharge-pipe L. Arranged within one-half of the annular passage and detachably secured to the casing is a backing M, 60 said backing being provided with laterally-extending lugs d, which abut against the shoulders e on the inclines. The lower wall of the section B is centrally apertured, as at f, and a similar aperture is formed within the 65 upper section C of the meter-casing. Within the aperture f is adjustably secured a post comprising an enlarged threaded portion g, arranged within the aperture, and a reduced portion or pin h, which extends within the 70 meter-casing.

The reference-letter i designates a threaded bushing adjustably arranged within the aperture formed in the upper section, and N designates the piston-shaft, comprising an enlarged portion j, having a socket formed therein, and a stem k. The socket is adapted to be arranged over the pin h, and the stem k extends through the bushing up into the 75 housing F. 80

The reference-letter l designates a gear-pinion arranged upon the end of the stem k, which is adapted to mesh with one of the gear-wheels of the usual reducing-gearing, which, being of ordinary construction and not constituting a part of this invention, is not shown. 85

The piston G is fixedly secured to the enlarged portion of the shaft N in any suitable manner and comprises in its construction an upper section O in the form of a plate or disk, 90 and a lower section P of similar form, each being centrally recessed to permit of their being sleeved over the shaft.

The lower section of the piston is provided with a depending annular ring a' and an inwardly-extending annular flange b', and between the flange and under face of the lower disk are arranged a series of spaced bosses c', as plainly shown in Fig. 1. Each boss is slotted, as shown, the slot extending entirely 95 100

through the boss and annular ring and into a portion of the lower disk, whereby a series of radial recesses d' are formed within the piston, in which are arranged a series of rectangular gates or wings Q. To prevent the liquid which enters the annular passage from entering the piston-chamber above the piston, we provide an annular flange c^2 upon the upper section of the piston, which extends within the recessed portion of the upper section of the casing and bears constantly against the casing. A similar flange f^2 is provided for the lower section of the piston, which acts as a guide to steady the movement of said piston. The liquid entering the casing below the piston is prevented from ascending by means of the peculiar construction of shaft that has heretofore been described.

20 The reference-letter R designates a cam, against which the inner ends of the rectangular wings are adapted to bear for the purpose of being projected outwardly across the annular passage in the path of the fluid. This 25 cam comprises a cam portion S, mounted upon standards T, the standards in turn being adjustably secured by means of bolts h' to the bottom of the meter-casing.

20 The meter having been thus described, the 30 operation of the same is as follows: The parts being arranged as in Fig. 2, the liquid entering through the supply-pipe K passes through the annular passage and striking against the wings extending in said passage causes the 35 piston to rotate. The incline I acts as a guide for the wings as they are forced out by the cam, while the incline J constitutes the means for returning the extended wings to their initial position, the portion of the cam 40 adjacent to said latter incline acting as a guide for the wings.

It will be observed from the construction of the mechanism as thus set forth that the 45 backing or wear-plate that we employ may be readily detached from the meter-casing and a new one substituted in its place when desired; likewise, that the cam may be adjusted as desired to compensate for wear or may be readily removed and a new cam inserted. It is also to be noticed that the parts 50 of the mechanism as set forth are simple in construction and few in number, producing a meter capable of being manufactured at a minimum cost.

55 In Fig. 5 we have shown another type of backing, which is in the form of a ring W, adapted to fit tightly within the annular passage. This ring is provided with inclines r and s , corresponding to inclines I and J, (shown 60 in Fig. 4, and with a reduced portion t , the inclines and the reduced portion upon the ring forming a passage leading from one inlet port to the other. The part of the ring opposite the reduced portion is adapted to entirely fill the annular passage and constitutes the wear-plate or backing for the piston.

What we claim as our invention is—

1. In a rotary meter, the combination of a cylindrical meter-casing having an inlet and an outlet port, a rotary piston of less diameter than the casing concentrically arranged within the latter forming an annular passage around the piston, a detachable backing within the annular passage extending from the inlet to the outlet port, a series of radially-arranged gates or wings carried by the piston, and a cam within the piston for operating said gates. 70

2. In a rotary meter, the combination of a cylindrical meter-casing, having an inlet and an outlet port, the upper and lower walls of said casing being centrally recessed, a rotary piston of less diameter than the casing, concentrically arranged within the latter and fitting and working in said recesses and forming an annular passage around the piston, the ends of said piston of less width than the piston fitting within the said recesses, a detachable backing within the annular passage extending from the inlet to the outlet port, a series of radially-arranged gates slidingly engaging the piston and working in said annular passage, and means for operating the gates. 85

3. In a rotary meter, the combination of a cylindrical meter-casing provided with an inlet and an outlet port, a rotary piston of less diameter than the casing arranged within the latter forming a passage around one side of the piston leading from the inlet to the outlet port, a series of radially-arranged gates within the piston and a cam, adjustably secured to said casing within said piston, for projecting the gates outwardly from the piston. 95

4. In a rotary meter the combination of a cylindrical meter-casing provided with an inlet and an outlet port, a rotary piston of less diameter than the casing arranged within the latter and forming a passage around the piston leading from the inlet to the outlet port, a series of radially-arranged gates within the piston, standards adjustably secured to the casing and extending within the piston and a cam mounted upon the standards and adapted to bear against the inner ends of the gates, substantially as described. 105

5. In a rotary meter, the combination of a cylindrical outer casing, provided with a central widened chamber and having an inlet and an outlet port, a rotary piston of less diameter than the casing concentrically arranged within the latter and fitting and working in said central enlarged chamber forming an annular passage around the piston of less width than the piston, a detachable backing in the form of a ring fitting within the annular passage, said ring having inclines formed thereon, arranged opposite the inlet and outlet ports, and a reduced portion connecting the inclines, a series of radially-arranged gates or wings within the piston, and means for operating said gates. 120

6. In a rotary meter the combination of a cylindrical casing provided with an inlet

and an outlet port, said casing comprising an upper and lower section, each centrally apertured an adjustable post carried by the lower section, said post comprising an enlarged threaded portion terminating in a reduced portion or pin, the threaded portion of the post engaging the aperture formed in said lower section and the pin projecting within the casing, an adjustable bushing fitting 5 within the aperture in the upper section, the piston-shaft comprising a socket-piece engaging over the pin, and a stem extending through the bushing, a piston fixedly secured to the shaft and a series of radially-arranged 10 gates or wings within the piston, substantially as described.

15 7. In a rotary meter, the combination of a

cylindrical meter-casing having an inlet and outlet port, a rotary piston of less diameter than the casing arranged within the latter to 20 form a passage around the piston, a detachable backing within the passage extending from the inlet to the outlet port, a series of radially-arranged gates or wings carried by the piston, and a cam within the piston for 25 operating the gates.

In testimony whereof we affix our signatures in presence of two witnesses.
